UNITED STATES PATENT OFFICE.

BENJAMIN F. BAILEY, OF MINNEAPOLIS, MINNESOTA, ASSIGNOR OF ONE-HALF TO
LIZZIE A. CREE, OF CHICAGO, ILLINOIS.

EGG-BOX.

1,171,083.

Specification of Letters Patent.

Patented Feb. 8, 1916.

Application filed June 9, 1915. Serial No. 33,055.

To all whom it may concern:

Be it known that I, BENJAMIN F. BAILEY, a citizen of the United States, and resident of Minneapolis, in the county of Hennepin 5 and State of Minnesota, have invented certain new and useful Improvements in Egg-Boxes, of which the following is a specification.

The object of my invention is to provide 10 a folding box in which any suitable number of eggs can be packed for safe transportation from place to place.

A further object is to provide a box which, when folded, will be of rigid construction 15 to resist external pressure and is adapted for convenient inspection of the eggs, such as subjecting them to the candling operation.

Other objects of the invention will appear 20 from the following detailed description.

The invention consists generally in an egg box substantially as described, and pointed out in the claims.

In the accompanying drawings forming 25 part of this specification, Figure 1 is a plan view of a blank cut and scored in accordance with my invention, Fig. 2 is a perspective view showing the blank half folded, Fig. 3 is a similar view showing the blank folded 30 ready to receive the eggs, Fig. 4 is a perspective view showing the blank completely folded and the folds locked together, Fig. 5 is a transverse sectional view through the box, Fig. 6 is a detail view looking at one 35 corner of the folded box.

In the drawing, the blank is shown rectangular, substantially, in form, and provided with parallel scored lines 2, 3, 4, 5 and 6, dividing the blank into panels 7, 8, 40 9, 10, 11 and 12. The panels 7 and 12, or the outer ones at the ends of the blank are provided with triangular flaps 13 having tongues 14 and 15 on the sides of the triangle and separated therefrom by the score 45 lines 16. These panels 7 and 12 also have a plurality of openings 17 therein with V-shaped tongues 18 formed around the edges of the openings and projecting into the openings. I have shown six of these openings in each panel to adapt the box for the insertion of half a dozen eggs therein, but this number may be increased or decreased as conditions may warrant or seem suitable.

The outer, longitudinal edges of the panels 55 7 and 12 also have tongues 19 thereon,

and at the inner longitudinal edges of these panels, locking tongues 20 are provided in staggered relation to one another and opposite each of these tongues on the panels 8 and 11 respectively are diagonally arranged 60 slits 21 adapted to receive the hooked or notched ends of the tongue 20 when the box is folded. Between the panels 9 and 10 and central with respect to the score line 4, I prefer to provide a slot 22 and upon 65 each side of this slot in the panels 9 and 10 I provide a pair of slits 23 substantially L-shaped, into which the ends of the tongues 19 are inserted in the final step of folding and locking the panels of the box together. 70 This panel is composed preferably of straw-board of suitable gage and when made by a machine will be cut out by suitable dies as the blank is fed through the rolls and when discharged from the machine will be 75 ready for the initial folding and the insertion of the eggs therein.

The first step in the folding operation is to bend the panel 7 on the scored line 2 until the three panels 7, 8 and 9 form a 80 V-shaped receptacle, the tongue 19 being inserted through the slot 22 as indicated in Fig. 2. When this has been done the panel 12 is folded in a similar manner and the longitudinal tongue of this panel is also 85 thrust through the slot 22 and the ends of the tongues inserted in the ends of the slits 23 and locked therein. The box will then assume the position shown in Fig. 3, and the eggs may be inserted into the openings 17, 90 the tongues 18 yielding under the pressure of the eggs and forming a cushion therefor. For these tongues, however, I make no claim in this application, as I am aware that they have been illustrated and generally used 95 prior to my invention.

When the panels 7, 8 and 9 are folded, the triangular flaps 13 are turned outwardly and the tongues 14 and 15 are inserted into the openings in the ends of the V-shaped egg 100 receptacle to close these ends and also support the panels against external pressure.

As soon as the eggs have been placed in the pockets therefor, one V-shaped receptacle is folded over on the central score line 135 4 until the holes therein register with the corresponding holes in the other pockets and the eggs will lie in these pockets substantially half in one and half in the other, as shown in Fig. 5, and be held by the 110

pockets and the tongues out of direct contact with the walls of the pockets and therefore be supported so that any external blow or pressure on the walls of the box will not 5 be transmitted directly to the fragile shells of the eggs.

When the final fold in the box has been made the tongues 20 will project from the inner longitudinal edges of the panels 7 and 10 12 and their hooked ends may be inserted into the opposite slits 21, and the V-shaped sections of the boxes thereby be locked together, while the walls will so brace and support one another that the box can be 15 safely transported from place to place without danger of breaking the eggs.

I also prefer to provide a series of notches at intervals along the scored lines 3 and 5, so that when the blank is folded to form the 20 box these notches will be opposite one another at each end of the eggs, and a person by holding up the box and looking through these notches toward a light can easily candle the eggs or determine whether they are 25 fresh or not. If the box is likely to be submitted to extreme rough handling it may be thrust into an outer casing of sufficient size to receive a plurality of the boxes. A suitable wrapper may then be placed on the 30 casing and it can be safely shipped by parcel post, express or by any other delivering means to any desired distance.

The blank may, of course, be made in various sizes and the details of the locking 35 of the panels together may be modified in various ways and still be within the scope of my invention.

I claim as my invention:

1. An egg box comprising a blank of 40 flexible material divided by parallel score lines into a series of panels, the outer panels at the ends of the blank having a plurality of openings therein and being folded initially along their score lines over the adjacent panels to form egg pockets triangular, substantially, in cross section, said pockets being folded finally upon one another when the eggs have been inserted therein, and said blank having tongues and slots for 45 locking said pockets in opposing relation to one another.

2. An egg box comprising a blank divided by parallel score lines into a plurality of panels, the outer panels having openings therein and triangular tongues at the 55 ends of said outer panels having flaps formed on the edges thereof, said outer panels being folded on their score lines over upon the adjacent panels to form egg pockets, triangular in cross section, the 60 tongues and flaps at the ends of said outer panels being inserted into said pockets for closing and bracing the open ends thereof.

3. An egg box comprising a blank divided by parallel score lines into a plurality of panels, the outer panels having openings therein and tongues formed on their outer longitudinal edges, said blank having a slot at the center thereof along the middle score line, said outer panels being 70 folded initially along their score lines over upon the adjacent panels to form egg pockets triangular, substantially, in cross section, the tongues of said outer panels being inserted through the slot in said blank and 75 interlocked with slits provided in the panels on opposite sides of said slot.

4. An egg box comprising a blank divided by transverse score lines into a plurality of panels, the outer panels having 80 openings therein, the next adjacent panels having tongues and slits formed therein in staggered relation, said outer panels being folded initially over upon the adjacent panels to form egg pockets and also folded 85 finally against one another with their openings in opposing relation, and said tongues being positioned after the final folding operation to enter the opposite slit for locking said egg pockets together.

5. An egg box comprising a blank scored to form a series of panels, the outer panels being folded along their score lines to form egg pockets, triangular in cross section, said pockets having opposing openings therein to 95 receive the eggs, the openings in each pocket being opposite one another with the eggs interposed between them, for the purpose specified.

In witness whereof, I have hereunto set 100 my hand this 4th day of June, 1915.

BENJAMIN F. BAILEY.
